UNITED STATES PATENT OFFICE.

ANTONY WELSCH, OF CHICAGO, ILLINOIS.

IMPROVEMENT IN RAILWAY DUMPING-CARS.

Specification forming part of Letters Patent No. 40,134, dated September 29, 1863.

To all whom it may concern:

Be it known that I, ANTONY WELSCH, of Chicago, in the county of Cook and State of Illinois, have invented a new and useful Improvement in Railway Dumping-Cars; and I do hereby declare that the following is a full, clear, and exact description of the construction and operation of the same, reference being had to the annexed drawings, making a part of this specification, in which—

Figure 1 is a ground plan; Fig. 2, a side view; Fig. 3, a front view, and Fig. 4 a front view with box lifted up.

The nature of my improvement consists in the bending of a shaft for friction-rollers, so that it is used to brace the frame above, and act as bearings for dumping-box, and also bearing for rollers, so that the car can be used for dumping at either sides or ends, and when not in use for dumping-car the box above can be removed and car used as a platform-car.

To enable others skilled in the art to make and to use my improvement, I will proceed to describe its construction and operation.

I construct the platform B and wheels A A

A A in the usual way, the socket C in center to receive center-bolt, and four rings, D D D D, at equidistant spaces, for hitching chain of dumping box on upper surface of platform.

E E E are friction-rollers, which carry shaft F and frame G, which last, by the connection of bearings H H from dumping-box J above, which rests on the ends of shaft below, rendering the box easily dumped at any desired point, and making it a universal dumper. The box J and frame for same are made in the usual way, with the exception of bearings for shaft and bracing-timbers. The car is also built low, thus doing away with the top weight in running, and is easier to load and unload.

What I claim as my invention, in the construction of dumping-cars, is—

The bearings H H, revolving on the end of a bent shaft that forms the axle for the friction-rollers E E, as and for the purposes herein described and set forth.

ANTONY WELSCH.
